UNITED STATES PATENT OFFICE.

CHARLES R. MORGAN, OF AKRON, OHIO.

FEED MECHANISM FOR SAW-TABLES.

SPECIFICATION forming part of Letters Patent No. 397,930, dated February 19, 1889.

Application filed April 30, 1888. Serial No. 272,341. (No model.)

To all whom it may concern:

Be it known that I, CHARLES R. MORGAN, of Akron, in the county of Summit and State of Ohio, have invented certain new and useful

5 Improvements in Feed Mechanism for Saw-Tables; and I do hereby declare the following to be a full, clear, and exact description of the invention, such as will enable others skilled in the art to which it pertains to make and use

10 the same.

My invention relates to improvements in feed mechanism for saw-tables; and it consists in certain features of construction and in combination of parts hereinafter described, 15 and pointed out in the claims.

In the accompanying drawings, Figure 1 is a plan. Fig. 2 is a side elevation in section on the line *xx*, Fig. 1. Fig. 3 is an end elevation, partly in section, on line *yy*, Fig. 1.

20 A represents the saw-table, including a suitable supporting-frame; *a*, a circular saw, and *a'* the gage, which, together with saw-mandrel, driving-pulley, &c., may all be of ordinary construction.

25 B is a metal sleeve in horizontal position and located crosswise and a few inches above the saw-table, the sleeve having a depending arm or flange, *B'*, the latter being secured to the one end of the saw-table frame and on 30 the side thereof opposite the saw. In the bore of sleeve *B* is journaled shaft *B*², the latter having a small head or collar, *B*³, that operates in the counterbore of the sleeve, the head or collar abutting shoulder *b*. On this 35 shaft are mounted sprocket-wheels *b'* and *b*², the hub of the latter abutting the end of sleeve *B*, by which arrangement of parts shaft *B*² is held endwise. On sleeve *B* is loosely mounted the one end of frame *C*. This frame 40 is in two sections, respectively, *C* and *C'*, the two sections being jointed at *c*, the adjacent ends of the two sections overlapping each other and secured by suitable bolt, pin, or stud, as the case may be, the axial line of the 45 joint being crosswise of the table. Boxes *d**d* and *d'**d'* are mounted on the respective frame-sections *C* and *C'*, the securing-bolts of these boxes passing through slots *c'* of the frame-sections, by means of which the boxes are 50 adjustable lengthwise of these frame-sections.

In these boxes are respectively journaled shafts *D* and *D'*. The boxes of both of these shafts, it will be observed, are located some distance from the ends or joints of the frame, so that in case it is ever desirable to remove 55 a section of the frame the shaft will not be in position to drop out of place, but, instead, will retain its former position. On the one end of these shafts and in line with the saw are feed-rollers *E* and *E'*, and on the other end 60 of these shafts are mounted sprocket-wheels *e* *e*, the latter being in line with sprocket-wheels *b'*, with endless chain *F*, connecting these three sprocket-wheels. By adjusting boxes *d**d* and *d'**d'* the stretch and wear of 65 the chain may be taken up and the chain kept sufficiently taut for practical purposes, and the alignment of the feed-rollers may be adjusted as desired.

In place of sprocket-wheels and endless 70 chain thereon for driving the feed-rolls, belts and pulleys or other power-transmitting mechanism may be substituted, if preferred. Sprocket-wheel *b*² is intended to receive an endless chain for driving the feed mechanism. Feed-roller *E* may have sharp teeth, and of such narrow face that the saw-kerf will cut away any marks left on the lumber by this feed-roll. Roller *E'* should have a broader face, and may have serrated or smooth 75 face, according as the lumber being slitted is rough or dressed, and it would be well to have two or more sets of feed-rollers, respectively, with rough and smooth surfaces adapted to different kinds of work and made interchangeable and easily detachable from shafts *D* and *D'*. Roller *E'* may have a circumferential 80 external flange, *E*², to follow in the saw-kerf to serve as a spreader to help guide the lumber. Frame *C C'* being, as aforesaid, jointed 85 in the middle and pivotally connected with the saw-table, can adjust itself vertically to accommodate the thickness of lumber, the weight of the frame and attachments being sufficient to hold the feed-rollers with sufficient force upon the surface of the lumber. Frame-sections *C* and *C'* are provided with vertically-adjusting screws *H*. The lower ends of these screws abut the table, and the upper ends of the screws are usually provided 90

100

with thumb-pieces or small hand-wheels for turning these screws. By adjusting these screws up or down the frame is held in position with the feed-rolls elevated from the table a sufficient distance to approximately accommodate the thickness of the lumber, so that when the rollers pass off from a piece of lumber they will only descend a short distance—perhaps an eighth of an inch, more or less—and will consequently be in position to readily mount the next piece of lumber.

The hubs of sprocket-wheels *e e* are made to abut the end of the adjacent boxes, and shafts *D D'* are provided with collars *D³* next inside these boxes, by which arrangement of parts these shafts are held endwise. The jointed frame is readily detachable from the saw-table, and may be removed bodily when not wanted by removing key *D⁴*, that holds the frame on sleeve *B*, and then slipping the frame endwise from off the sleeve. The operator has only to adjust gage *a'* according to the width of lumber wanted and insert the plank or board under roller *E*, after which the feed-rollers will take care of the lumber, leaving the operator free to handle the next piece of lumber, thus saving much time and saving the labor of one man over the old method of feeding by hand.

30 The lumber during the slitting operation being held upon the table by the feed-rolls and being fed uniformly, and the operator

having no occasion to come in close proximity to the saw, the liability to accident is reduced to a minimum.

What I claim is—

1. The combination, with a saw-table, of a jointed frame pivotally connected at one end to the table, shafts journaled in each section away from the joining-point, and rollers on 40 said shafts, substantially as set forth.

2. The combination, with upright arm rigidly connected with the saw-table, said arm being integral with an overhanging sleeve extending crosswise of the table, of jointed 45 frame removably mounted on the said sleeve, and feed mechanism journaled in said jointed frame, substantially as set forth.

3. The combination, with upright arm, a laterally-projecting sleeve integral therewith, 50 a jointed frame mounted on the sleeve, and feed mechanism journaled in said jointed frame, of a shaft journaled in the bore of such sleeve, said shaft being operatively connected with the feed mechanism and with the 55 jointed frame, substantially as set forth.

In testimony whereof I sign this specification, in the presence of two witnesses, this 31st day of December, 1887.

CHARLES R. MORGAN.
